Attorney

UNITED STATES PATENT OFFICE

HOWARD GRAHAM, OF DALLAS, TEXAS

HERNIAL TRUSS

Application filed December 6, 1928. Serial No. 324,158.

The invention relates to hernial trusses and has for its principal object the provision of a truss employing a bow member to fit on the hip of the wearer and having a hernial pad secured at one end of the bow member, the other end of the bow member being formed at an angle to the adjacent portion of the bow member and having a blind pad mounted thereon to engage in the hip socket, 5 pad secured at one end of the bow member, the other end of the bow member being formed at an angle to the adjacent portion of the bow member and having a blind pad mounted thereon to engage in the hip socket, 10 a belt being also provided that is secured at one end to said angularly formed portion of the bow and having its other end adapted to be secured at the same end of the bow as that carrying the hernial pad.

15 A further object of the invention is the provision of a hernial truss having a pad member with a suitable support, said pad member being mounted on the support by means of a stem having limited universal connection 20 with the pad, and providing a spring cushion engaging the pad and the support to cushion the movement of the pad to different positions.

25 The invention will be described in detail hereinafter and will be found illustrated in the accompanying drawings in which

Figure 1 is a top plan view of the improved hernial truss,

Figure 2 is a sectional detail of the hernial pad on a plane indicated by the line 2—2 of Figure 1, and

Figure 3 is a fragmentary side view of one end of the bow.

In the drawings similar reference characters are used to designate corresponding parts throughout the several views.

The hernial truss is of a type employing a bow 1 to enclose the hip of the wearer, said bow being preferably made of a rigid bar 2 shaped to properly fit the hip of the wearer and enclosed by rubber or other suitable non-chafing casing 3. At one end the bow is bent downwardly as shown at 4, to provide a portion 5, depending at an angle to the remainder 40 of the bow, and mounted on the portion 5 is a pad 6 having a loop 7 to engage said portion 5 and held in position thereon by means of a threaded nut 8 engaging the threaded portion 9 on the extremity of the bow. The 45 depending portion 5 provides means by which the bow may engage the body above the hip bone and permit the pad 6 to engage below the waist so that the article may be comfortably worn, without danger of downward displacement and pressure to hold the hernial pad, hereinafter described, secured in position is assured. 10 indicates a belt having one end provided with a loop 11 to engage the angular portion 5 of the bow, 12 indicating a buckle mounted on a strap 13 that is connected with a loop member 14, the buckle 12 admitting of adjustment of the length of the belt 10 so that the belt 10 may be passed around the body of the wearer to hold the bow 1 in position on the hip. The pad 6 55 when in position on the hip engages in the hip socket and serves to properly position the bow for comfortable wearing of the hernial pad 15. This pad 15 has a base plate 16 with a central opening 17, the base plate 16 being 60 provided with an outwardly offset portion 18 forming the walls of the opening, said portion 18 being formed at an angle as shown, and the opening 17 is designed to receive the stem 19 having its outer end provided with 65 threads 20, said threaded portion 20 being also reduced and formed with a transverse opening 21 in which is fitted the end 22 of the bar 2, said end having its outer portion flattened as shown at 23. 24 indicates a nut 70 that is screwed onto the threads 20 and engaging the flattened portion 23 in the end 22 to clamp the stem 19 in position thereon. The outer extremity of the stem 19 is formed 75 with a headed stud 25 that is engaged by the loop 14 to secure the belt in position as heretofore stated. 26 indicates another plate that is secured to the base plate 16 by means of studs or threaded members 27, said plate 26 being provided with a recess or depression 80 28 opposite the head 29 of the stem 19, the offset inclined walls surrounding the opening 17 and the depression 28 in the plate 26 provides a socket for limited universal movement of the pad 15 on the stem 19, 30 indicates an expandable coil spring surrounding the stem 19 and terminally engaging the plate 16 and nut 24 to cushion the movement 85 of the pad 15. 31 indicates a cushioning material of the pad 15 and 32 the cover for the 90 95 100

pad, the edges of said cover being secured between the plates 16 and 26 as clearly shown in Figure 2.

It will be apparent that the nut 24 performs a dual function of holding the stem 19 in position on the end 22 of the bar 2 and also provides a thrust bearing for the outer end of the spring 30.

What is claimed is:—

- 10 A hernial pad, comprising a base plate of rigid material having an opening therein, the plate surrounding said opening being outwardly deflected, a stem movably mounted in said opening, a head on the stem to seat in said deflected portion, another plate secured 15 to said base plate and having a recess to receive said head, cushion material mounted on the last mentioned plate, a cover for said cushion material, the edges of said cover secured between said plates, means to support the pad, 20 and a spring enclosing the stem and terminally engaging the supporting means and the base plate to cushion the movement of said pad on the stem.

25 In testimony whereof I affix my signature.
HOWARD GRAHAM.
